BED SPRING SUPPORT.

APPLICATION FILED MAR. 28, 1907.

2 SHEETS—SHEET 2.

UNITED STATES PATENT OFFICE.

EDWARD RYAN, OF CLINTON, IOWA.

BED-SPRING SUPPORT.

No. 876,096.

Specification of Letters Patent.

Patented Jan. 7, 1908.

Application filed March 28, 1907. Serial No. 365,038.

To all whom it may concern:

Be it known that I, EDWARD RYAN, a citizen of the United States, residing at Clinton, in the county of Clinton and State of Iowa, have invented certain new and useful Improvements in Bed-Spring Supports; and I do declare the following to be a full, clear, and exact description of the invention, such as will enable others skilled in the art to 10 which it appertains to make and use the same.

My invention relates to improvements in bed-spring supports, which reinforce the bed-spring fabric to prevent the same from 15 sagging, and which are capable of adjustment so that the said supports may be put under any required tension and may be relieved of tension when the bed is in storage and not in use so as to avoid springing 20 or warping the frame, and which when in use may be adjusted to suit the unequal weight of two persons occupying the same bed, and my invention consists in the construction, combination and arrangement of 25 devices hereinafter described and claimed.

In the accompanying drawings, Figure 1 is an inverted plan view of a spring bed bottom provided with adjustable supports embodying my invention; Fig. 2 is a longitudinal sectional view of the same; Fig. 3 is a detail elevation of a modified form of the tension and adjusting devices for the supporting reinforcing wire; and Figs. 4, 5, 6, 7 and 8 are detail elevations of modified forms 35 of the tension springs used in connection with such wires.

The frame of the bed spring is indicated at 1 and the bed bottom fabric, which may be of any suitable construction, is indicated at 2. In accordance with my invention, I provide a suitable number of longitudinally-disposed supporting reinforcing wires 3, each of which has a hook 3^a formed at one end, and has its opposite end screw-threaded. 40 The same are here shown as having their major portions run through the bed spring fabric and as having their ends inclined downwardly therefrom. To the opposite ends of the frame 1 are attached hooks 4, each of which has a bill 5 at its outer end inserted in an opening in one end of the frame and also has a reversely-disposed bill 6 at its inner end. The intermediate portions of the said hooks rest on the upper sides 45 of the cross bars which form the ends of the

frame. The wires 3 are each attached by its hook at one end to a bar 7, which is here shown as an angle iron disposed transversely under the bed spring fabric near one end thereof. The ends of the said bar are attached to tension and adjusting devices 8, each of which is composed of a plurality of angle link members 9. In the form of my invention shown in Fig. 1, each tension and adjusting device has a pair of said angle link members pivotally connected together, as at 10, one of said members being pivotally connected to the bar 7, and the other being attached to the bill 6 of one of the hooks 4. An adjusting screw 11 passes through openings in the said angle links and is provided at one end with an adjusting nut 12. Springs 13 coact with the said link members and the said adjusting screws to normally draw the said link members toward each other 75 to apply tension to the wires 3. The said springs are here shown as coiled springs mounted on the ends of the said screws, one of said springs bearing between the head of one of the screws and one of the link members 9, 80 the other spring bearing between the other link member and the adjusting nut.

The opposite end of each wire 3 passes through the down-turned, bent portion 14 of a tension yoke 15, which is U-shaped and 85 made of a single piece of wire. On the said end of the said wire 3 is screwed an adjusting nut 16. Washers 17 are placed on said wire, one of which bears against said nut 16, the other bearing against the down-turned portion 14 of the tension yoke. A coiled spring 18 on the said end of the wire 3 bears between the said washers. Said tension yoke is attached to a tension spring 19, which may be of any suitable form, various forms of said 95 spring being shown in Figs. 4, 5, 6, 7 and 8. The said tension spring is formed with a plurality of spring coils 20 and is connected to the end of the frame opposite that to which the tension and adjusting devices 8 are connected by being attached to one of the hooks 4. It will be understood that by turning the nuts 12, 16 to vary the tension of the springs 13, 18 and 19, the wires 3 may be put under 100 the desired degree of longitudinal tension or stress and hence caused to reinforce the spring bed fabric to any desired extent. Furthermore, the said wires 3 may be put under unequal degrees of tension to accommodate 105 the bed bottom to persons of unequal weight. 110

In the modified form of tension adjusting device shown in Fig. 3, said device has two pairs of pivotally-connected angle links 9^a,

In each of the forms of the spring shown in Figs. 4, 5, 6, 7 and 8, the spring is made of a single piece of spring wire, bent into the required shape and also bent to form a plurality of spring coils 20 between which the stress is distributed, and the ends of which merge in link or arm portions 22, which connect said coils together and move angularly with reference to one another under variations of the stress exerted on the spring. Such provision of a plurality of coils and of angularly movable coil-connecting portions renders such springs extremely strong and flexible. In each of the forms of the spring shown in Figs. 5, 6 and 7, the ends of the wire of which the spring is made are directly connected together, as shown at 23.

In the form of the spring shown in Fig. 4, the wire of which it is composed is bent to form two oppositely-extending arms 24, in the outer end of each of which is a relatively large coil 20^a. The connecting portions between said arms include a relatively small coil 20^b. The end portions 25 of said spring are bent from the said arms and disposed in parallel relation and terminate in hooks 26 which engage openings in the ends of a spring plate 27, which connects said end portions together. Said spring plate has a central opening 28 (indicated in dotted lines) for the reception of the threaded end of one of the reinforcing supporting wires 3.

While I have herein described my invention as applicable to a bed spring, it will be understood that the same may be used in connection with springs for other articles of furniture. It will be observed by reference to the drawings that my improved tension and adjusting devices are disposed under the

spring where they are readily accessible and may be readily adjusted.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention, as defined by the appended claims.

Having thus described my invention, what I claim as new, and desire to secure by Letter-Patent is,—

1. In combination with a bed or the like spring fabric and a frame on which the same is stretched, a supporting reinforcing wire for the spring fabric, attached to the frame, and a tension and adjusting device for said wire, connected thereto and to the frame and having pivotally connected angle links, an adjusting screw connecting said links, and springs coacting with said screw and links to exert tension on said wire.

2. In a structure of the class described, a spring for the purpose set forth, made of a single wire bent to form oppositely-extending arms, spring coils at the outer ends of said arms, a connecting portion between said arms having a centrally disposed spring coil, and terminal parallel portions, and a spring plate connecting the ends of said parallel portions.

In testimony whereof I have hereunto set my hand in presence of two subscribing witnesses.

EDWARD RYAN.
